DESIGN FOR A SHOE

Anthony H. Geuting, Philadelphia, Pa.

Application January 5, 1939, Serial No. 82,178

Term of patent 14 years

To all whom it may concern:

Be it known that I, Anthony H. Geuting, a citizen of the United States of America, residing at Philadelphia, in the county of Philadelphia and State of Pennsylvania, have invented a new, original, and ornamental Design for a Shoe, of which the following is a specification, reference being had to the accompanying drawing, forming part thereof, in which:

Fig. 1 is a view in elevation of the inner side of a shoe showing my new design.

Fig. 2 is a view in elevation of the outer side of the shoe.

The essential features of my design comprise stitching arranged in a manner as shown on the inner side of the upper quarter of the specific type of a shoe as herein illustrated.

I claim:

The ornamental design for a shoe, as shown and described.

ANTHONY H. GEUTING.
